ASSEMBLY FOR PUMPING WELL FLUIDS

Curtis L. Massey, Jacksonville, Tex.

Application July 5, 1957, Serial No. 670,107

7 Claims. (Cl. 103—4)

The present invention is directed to an assembly for pumping well fluids. More particularly, the invention is concerned with a hydraulically operated well pump which is movable through and seatable in a well tubing. In its more specific aspects, the invention is concerned with an assembly for pumping well fluids in which means are provided for fluidly interconnecting conduits through which hydraulic fluid is supplied to the pumping assembly and removed therefrom.

The present invention may be briefly described as an assembly for pumping well fluids which comprises at least one hydraulically operated well pump which is movable through and seatable in a well tubing. A first conduit is attached to the well tubing for delivering hydraulic fluid to the pump and a second conduit is also attached to the well tubing for conducting the hydraulic fluid and the well fluids from the pump. The two conduits communicate fluidly with the pump. Means are provided, such as a third conduit, which fluidly interconnects the first and second conduits adjacent the pump. In the fluid interconnecting means, or the third conduit, is provided a flow control means which may suitably be a check valve which permits flow through the fluid interconnecting means in one direction and resists flow through the fluid interconnecting means in another direction. In short, the flow control means allows flow from the second conduit to the first conduit and resists flow from the first conduit to the second conduit whereby fluid circulation from the second conduit to the first conduit is conducted while maintaining the pump seated in the well tubing.

The present invention is of considerable advantage and utility in that heretofore when the conduit or line carrying production and power or hydraulic fluids from the hydraulically operated pump became fouled by deposition of wax, and the like, it was necessary, when running a soluble plug through the line to remove the fouling material, to unseat the hydraulically operated pump and then reseat it by virtue of the pressure employed to move the soluble plug through the line. In the practice of the present invention, wherein the conduit which normally supplies power fluid and the conduit which normally discharges production and power fluids are interconnected and a flow control means, such as a check valve provided therein, it is possible to run the soluble plug without unseating the pump. Besides saving a considerable amount of time for unseating and reseating the pump with the consequent wear on pump packing, there is no commingling of fluids where the invention is employed in a dually completed well employing a plurality of interconnected pumps. The invention is therefore of considerable advantage and is quite useful in such installations.

The present invention will be further described by reference to the drawing in which the single figure is a partial sectional view of a preferred embodiment. Referring now to the drawing, numeral 11 designates a well casing located in a well bore drilled from the earth's surface, not shown, and cemented in place using the

2

usual conventional cementing technique. For purposes of description and for simplicity, the cement shield or sheath surrounding the casing 11 is not shown. The well casing 11 is arranged in the well bore 12 which penetrates a plurality of subsurface earth formations, sands, zones, horizons, strata, and the like, some of which may be hydrocarbon bearing and others of which are non-hydrocarbon bearing. For purposes of this description only, it may be assumed that zone or horizon 13 is hydrocarbon bearing and zone or horizon 14 is non-hydrocarbon bearing and zone or horizon 15 contains hydrocarbons. It may be further assumed that zones or horizons 13 and 15 are vertically spaced apart a substantial distance, and it is desirable to produce oil simultaneously from both of the zones.

In accordance with the present invention, a tubing string 16 having a housing 17 arranged on its lower end and forming a part thereof is provided with a first bypass conduit 18 and a second bypass conduit 19. The lower end of the housing 17 is arranged in a packer 20 which separates and isolates the zones 13 and 15 one from the other. Connected to the housing 17 is a first conduit 21 for supplying power fluid through lateral conduits 22 and 23 to the housing 17 and to hydraulically operated pumps, which will be described further hereinafter. Also connected to the housing 17 is a second conduit 24 which connects to the housing 17 by lateral conduits 25 and 26. The conduits 24, 25 and 26 serve to remove power and production fluid from the housing 17 and from the pump, which will be described further hereinafter. Interconnecting the conduits 21 and 24 is a third conduit 27 which contains a check valve 28. Check valve 28 allows fluid to flow from conduit 24 to conduit 21 when a sufficient amount of pressure is exerted on the check valve to cause the check valve to unseat. Check valve 28 resists flow of fluid from conduit 21 to conduit 24.

Arranged in the lower portion of the housing 17 is a crossover means generally designated by the numeral 29, which is seatable or supported in a seating means 30 which may be a landing nipple. The crossover means 29 is suitably supported or anchored in the landing nipple 30 by a hanger 31. The crossover means 29 is sealed in the housing 17 by sealing means 32, 33, 34 and 35. The lower end of the crossover means 29 is open and provides communication with a passageway 36 which in turn communicates through ports 37 with the space 38 between sealing means 33 and 34 and thence by port 39 with the bypass conduit 18, the plug 40 closing the passageway 36.

The housing 17 is provided with a port 41 communicating with the space 42 between packing or sealing means 34 and 35 and with the ports 43 and with passageway 44 above the plug 40 and thence with one of the pumps which will be described hereinafter. The upper end of the crossover means 29 is provided with a suitable fishing head 45 for retrieving the crossover means 29 with a wire line as may be desired.

Movable through the tubing 16 and the housing 17 and seated within the upper end 45 of the crossover means 29 are interconnected pumps 46 and 47. These pumps are interconnected for running in of the pumps and for seating of the pumps in the upper end 45 of the crossover means 29. The pumps 46 and 47 are suitably restrained and seated within the crossover means 29 by a restraining means 48, which may be a latch or anchor and which is sealed by sealing means 49 with the inner wall of the passageway 44.

The interconnected pumps 46 and 47 are provided with a suitable fishing neck 50 provided with a fishing head 51 for retrieving the interconnected pumps 46 and 47 from the housing 17 as may be desired.

The pump 46 is provided with sealing means 52 and 53 which serve to isolate the ports 54 and to provide communication with the conduits 23 and 21. Sealing means 55 on pump 47 cooperates with sealing means 53 on pump 46 and isolates the ports 56 of pump 47 from the ports 54 of pump 46. Sealing means 57 on pump 47 isolates the ports 58 from the ports 59. Sealing means 60 on pump 47, in cooperation with sealing means 61, isolates the ports 62 and allows communication between the pump 47 and the conduits 22 and 21.

It will be seen from the foregoing description that the ports 62 communicate with the conduit 22, the ports 59 communicate with the conduit 25, the ports 58 communicate through port 63 with the by-pass conduit 19, which in turn communicates through port 64 with the tubing 16 for passage to the earth's surface.

With the assembly as set out in the drawing, it is possible to pump fluids from the zones 13 and 15 simultaneously. Fluid from the lower zone 15 flows through perforations 15a in casing 11 and then passes through the passageway 36 through port 37 into the space 38 and thence through port 39 into by-pass conduit 18 and thence by port 65 into the space 66 and then into ports 56 which constitute the inlet to pump 47 and discharged by way of ports 58 into the port 63 and thence through by-pass conduit 19 and port 64 upwardly through the tubing 16.

Production from the upper zone 13 proceeds into the annulus A between the housing 17 and the casing 11 and through perforations 13a in casing 11 and thence through inlet port 41 into space 42 and into passageway 44 and thence into the inlet 67 of pump 46 to be discharged by way of port 68 into the space 69 between sealing means 35 and 52 and thence into conduits 26 and 24 to the earth's surface, the power oil and the produced fluid from zone 13 commingling and being discharged to the earth's surface. Also, the power fluid supplied to pump 47 is discharged through port 59 into the space 70 which is in communication with the conduit 24 for discharge of the power fluid.

During the operation of a pumping assembly of the nature described herein, the conduit 24, which may be about 1" in diameter, will tend to become fouled with waxy and other materials which deposit from the produced oil. When this happens, it has been necessary heretofore to place a soluble plug of material in the equivalent of line 24 where the present invention was not employed and to superimpose fluid pressure on the plug and pump it down the equivalent of line 24. Since pressure is exerted then on the sealing means, such as 52, this would cause unseating of the pumps 46 and 47, overcoming the restraining means 48 and also would require, prior to the present invention, subsequent reseating of the pumps 46 and 47. Wear would be effected on the several sealing means which would require replacement.

In accordance with the present invention, by provision of the conduit 27 and the check valve 28, the pumps 46 and 47 do not become unseated. A soluble plug is placed in the conduit 24 and fluid pump pressure is exerted, pumping power fluid down the conduit 24. Since the pressure is sufficient to overcome the force of the spring loaded check valve 28 but less than that required to unseat pumps 46 and 47 by overcoming restraining means 48, the check valve 28 becomes unseated and the pumped power fluid down line 24 causes the pumped fluid to flow through line 21 to the earth's surface, which is the reverse of the normal fluid flow. The soluble plug removes the wax or other deposited material from the inner wall of the conduit 24 and by virtue of its solubility in the power oil slowly dissolves and/or becomes melted due to the temperature in the annulus A and flows commingled with the pumped power fluid through the check valve 28 and through the conduit 21 to the earth's surface.

The type of soluble plug employed in the practice of 75

the present invention may be of the type described in the Coberly Patent 2,761,514, columns 6 and 7, where an oil soluble sealing means is described. Briefly, natural asphalts, naphthalenes, high melting point waxes, partially polymerized natural resins, asphaltic emulsions, sulfur, and the like, may be used. Other oil soluble and heat meltable materials may be used in lieu of the several specific materials mentioned before.

The present invention has been used successfully and has resulted in substantial savings in a dually completed well.

The nature and objects of the present invention having been completely described and illustrated, what I wish to claim as new and useful and secure by Letters Patent is:

1. In an assembly for pumping well fluids in a well having a tubing arranged therein comprising at least one hydraulically operated well pump freely movable through and seatable releasably in said tubing at a point adjacent the lower end thereof, in which said well is provided with a first conduit and a second conduit attached to said tubing adjacent said point, the first of said conduits being adapted for delivering hydraulic fluid to said pump and the second of said conduits being adapted for conducting said hydraulic and well fluids from said pump, said conduits communicating fluidly with said pump, means arranged exteriorly of said tubing fluidly interconnecting said conduits adjacent the lower ends thereof, and a spring-loaded check valve means in said fluid interconnecting means providing unidirectional flow from the second conduit through said fluid interconnecting means to the first conduit, said spring-loaded check valve means being constructed to open at a pressure less than that which would release said pump from its seat in said tubing, whereby fluid circulation from the second of said conduits to the first of said conduits is conducted while maintaining pump seated in said tubing.

2. In an assembly for pumping well fluids in a well having a tubing arranged therein comprising at least one hydraulically operated well pump freely movable through and seatable releasably in said tubing at a point adjacent the lower end thereof, in which said well is provided with a first conduit attached to said tubing for delivering hydraulic fluid to said pump and with a second conduit attached to said tubing for conducting said hydraulic and well fluids from said pump, said conduits being attached to said tubing adjacent said point and said conduits communicating fluidly with said pump, means arranged exteriorly of said tubing fluidly interconnecting said conduits in said well adjacent said pump and a spring-loaded check valve means in said fluid interconnecting means providing unidirectional flow through said fluid interconnecting means from the second conduit to the first conduit, said spring-loaded check valve means being constructed to open at a pressure less than that which would release said pump from its seat in said tubing, whereby fluid circulation from the second conduit to the first conduit is conducted while maintaining said pump seated in said tubing.

3. In an assembly for pumping well fluids in a well having a tubing arranged therein comprising a plurality of interconnected hydraulically operated well pumps freely movable through and seatable releasably in said tubing at a point adjacent the lower end thereof in which said pumps are provided with a first conduit and a second conduit attached to said tubing adjacent the lower end thereof, the first of said conduits being adapted for delivering hydraulic fluid to said pumps and the second of said conduits being adapted for conducting said hydraulic and well fluids from said pumps, said conduits communicating fluidly with said pumps, means arranged exteriorly of said tubing fluidly interconnecting said conduits adjacent the lower ends thereof, and a spring-loaded check valve means in said fluid interconnecting means providing unidirectional flow through said fluid interconnecting means from the second conduit to the first conduit, said spring-loaded check valve means being constructed to open at a

pressure less than that which would release said pumps from their seats in said tubing, whereby fluid circulation from second of said conduits to the first of said conduits is conducted while maintaining said pumps seated in said tubing.

4. In an assembly for pumping well fluids in a well having a tubing arranged therein comprising a plurality of interconnected hydraulically operated well pumps freely movable through and seatable releasably in said tubing at a point adjacent the lower end thereof, in which said pumps are provided with a first conduit attached to said tubing for delivering hydraulic fluid to said pumps and with a second conduit attached to said tubing for conducting said hydraulic and well fluids from said pumps, said conduits being attached to said tubing adjacent said point and said conduits communicating fluidly with said pumps, means arranged exteriorly of said tubing fluidly interconnecting said conduits in said well adjacent said pumps and a spring-loaded check valve means in said fluid interconnecting means providing unidirectional flow through said fluid interconnecting means from the second conduit to the first conduit, said spring-loaded check valve means being constructed to open at a pressure less than that which would release said pumps from their seats in said tubing, whereby fluid circulation from the second conduit to the first conduit is conducted while maintaining said pumps seated in said tubing.

5. An assembly for pumping well fluids comprising, in combination, a well tubing, at least one hydraulically operated well pump freely movable through and seatable releasably in said well tubing adjacent its lower end, a first conduit and a second conduit attached to said tubing adjacent the lower end thereof, the first of said conduits being adapted for delivering hydraulic fluid to said pump and the second of said conduits being adapted for conducting said hydraulic and well fluids from said pump, said conduits communicating fluidly with said pump, means arranged exteriorly of said tubing fluidly interconnecting said conduits in said well adjacent said pump, and a spring-loaded check valve means in said fluid interconnecting means providing unidirectional flow through said fluid interconnecting means from the second conduit to the first conduit, said spring-loaded check valve means being constructed to open at a pressure less than that which would release said pump from its seat in said tubing, whereby fluid circulation from the second of said conduits to the first of said conduits is conducted while maintaining said pump seated in said tubing.

6. An assembly for pumping well fluids comprising, in combination, a well tubing, a plurality of hydraulically op-

erated well pumps freely movable through and seatable releasably in said well tubing adjacent its lower end, a first conduit attached to said tubing for delivering hydraulic fluid to said pumps and with a second conduit attached to said tubing for conducting said hydraulic and well fluids from said pumps, said conduits being attached to said tubing adjacent said pumps and said conduits communicating fluidly with said pumps, means arranged exteriorly of said tubing fluidly interconnecting said conduits adjacent said pumps in said well and a spring-loaded check valve means in said fluid interconnecting means providing unidirectional flow through said fluid interconnecting means from the second conduit to the first conduit, said spring-loaded check valve means being constructed to open at a pressure less than that which would release said pumps from their seats in said tubing, whereby fluid circulation from the second conduit to the first conduit is conducted while maintaining said pumps seated in said tubing.

20 7. An assembly for pumping well fluids comprising, in combination, a well tubing at least one hydraulically operated well pump freely movable through and seatable releasably in said well tubing adjacent its lower end, a first conduit attached to said tubing for delivering hydraulic fluid to said pump and with a second conduit attached to said tubing for conducting said hydraulic and well fluids from said pump, said conduits being attached to said tubing adjacent said pump and said conduits communicating fluidly with said pump, a third conduit 25 on the exterior of the tubing fluidly interconnecting said first and second conduits in said well adjacent said pump, and a spring-loaded check valve in said third conduit providing unidirectional flow through said third conduit from the second conduit to the first conduit, said spring-loaded check valve being constructed to open at a pressure less than that which would release said pump from its seat in said tubing, whereby fluid circulation from the second conduit to the first conduit is conducted while maintaining said pump seated in said tubing.
